ROTARY PRESSURE VESSELS

Robert M. Donaldson, Hampton, Va., assignor to Newport News Shipbuilding and Dry Dock Company, Newport News, Va., a corporation of Virginia

Filed Jan. 31, 1956, Ser. No. 562,465

12 Claims. (Cl. 34—124)

This invention relates to driers of the type commonly referred to as "Yankee" driers and relates with more particularity to structural improvements therein which inherently provide better and specifically more rapid heat transfer characteristics than were heretofore possible while at the same time imparting sufficient structural rigidity thereto as to lie within the acceptable code for safety requirements.

This invention contemplates the use of "Yankee" driers having a much thinner shell thickness than conventional driers. The thinner shell provides, assuming the same internal steam temperature as for a drier having a thicker shell, a greater rate of heat transfer than the thick-shelled drier. This will permit a much greater rate of production to be accomplished in the paper making industry.

However, a "Yankee" drier having a shell thickness and diameter of the magnitude contemplated by this invention must depart radically in structural detail from those constructions employed in conventional practice.

It is therefore an object of this invention to provide an improved form of "Yankee" drier embodying a thinner shell section than has been heretofore attainable in the prior art.

Another object of this invention is to provide an improved drier including a thin outer cylindrical shell closed at its opposite ends by a pair of heads, the heads being interconnected by an internal flue and in which only one of the heads is connected directly to the shell to minimize the transfer of stresses between the heads and the shell.

Another object of the invention resides in the construction in accordance with the preceding paragraph in which a circular bearing is interposed between the unanchored head and the inner surface of the shell to permit relative movement therebetween.

Still another object of this invention is to provide improvements in "Yankee" driers embodying an outer cylindrical shell having a flue disposed concentrically within the shell connected at one end to the corresponding end of the shell by a head portion, there also being a head rigid with the other end of the flue carrying a ring-like bearing engaging the inner surface of the shell and permitting relative movement between the other head and the shell so as to obviate the transfer of stresses therebetween, the flue being of substantial diameter with respect to the shell and serving to rigidify the heads and maintain the bearing in proper contact with the inner surface of the shell.

Another object of this invention is to provide a drier in conformity with the preceding object wherein the shell thickness is in the order of $1\frac{1}{2}$ inches; the shell diameter is in the order of 12 feet; the flue diameter is in the order of from 60%—75% of the shell diameter; the ratio of flue thickness to shell thickness is in the order of from 1.25 to 1—2.0 to 1; and the ratio of head thickness to shell thickness is in the order of from 1.5 to 1—2.5 to 1.

A further object of this invention resides in an improved "Yankee" drier embodying a slip joint connection between one of its heads and the outer shell, the other

2

head being joined directly to the shell and the two heads being rigidly joined by an intervening flue.

Still another object of this invention lies in an improved drier constructed in accordance with the preceding object wherein the slip joint includes a ring-like bearing interposed between the shell and the unanchored head and a sealing ring of semicircular cross section rigidly connected to both such head and the shell, the sealing ring being constructed of deformable material to allow for relative movement between the head and shell.

The figure of the drawing is a longitudinal section taken through one form of drier constructed in accordance with this invention.

Referring now more particularly to the figure of the drawing, the form of drier shown therein includes an outer shell or drum 10 which is of generally cylindrical configuration and which is provided at its opposite open ends with the inturned flanges 11 and 12. These two flanges serve to provide means by which the two heads, indicated generally by the reference characters 13 and 14, are operatively related to the shell. Although the heads, in the specific embodiment shown, are illustrated as being integrally formed with the flue structure, indicated generally by reference character 15, it will nevertheless be understood that the heads may be formed as separate members, either in whole or in part, which are secured at their outer edges to the shell and which are also connected to the flue for locating the same in proper relation to the shell.

The flue as shown consists of three separable parts, a pair of identically formed end sections which include the aforementioned heads, and a central section which joins and interconnects the two end sections. Each end section incorporates an axially extending and outwardly projecting shaft or journal 16 received in suitable bearings as indicated by the dotted line structure for rotatably mounting the drier in horizontal position as shown.

Each such shaft is hollow and serves as an external connection to one of the two separate internal chambers 17 and 18 within the flue and each shaft is rigid with or formed integrally with the central or hub portion 19 of its associated flue end section.

Each flue end section also includes an inwardly directed cylindrical portion 20 terminating in an outturned flange 21, which flanges define the parting line between the end sections and the central flue section. The central section is in the form of a cylindrical body 22 having outturned flanges 23 and 24 at its opposite ends joined to the flanges 21 of the end sections by means of suitable fasteners 25.

Centrally located within the center section is a partition wall or baffle 26 having in the specific embodiment shown a central opening 27 normally closed by the removable cover plate 28. Thus, the baffle serves to isolate the two previously mentioned chambers 17 and 18. On opposite sides of the baffle are formed a series of openings 29 and 30 in the body 22 of the center section so as to communicate the two chambers 17 and 18 with the annular chamber 31 formed between the flue and the inner surface of the shell 10.

In use, steam under pressure is introduced into one chamber through the corresponding shaft 16 whence the steam flows into one of the chambers 17 or 18 and outwardly thereof through either the openings 29 or 30 into the annular chamber 31 to heat the shell 10. The steam is then forced from the annular chamber 31 into the other flue chamber 17 or 18 and thence outwardly through the corresponding shaft 16.

The end sections of the flue include, in addition to the above mentioned parts, the generally radially extending annular portions 32 and these may be formed as shown integrally with the remainder of the flue end sections.

Each annular portion 32, together with its corresponding central section 19, constitutes and presents what may be termed a head for the corresponding end of the shell 10. Additionally, each flue end section may include a number of generally triangular, radially extending reinforcing ribs 35 joining the annular head portion 32 with its associated cylindrical portion 20.

From the drawing it will be apparent that the wall thickness of the flue structure is rather massive when compared with the wall thickness of the shell and that the diameter of the flue is quite large. These two features cooperate to render the central portion 19 of each head substantially rigid but more important, deformation of the heads at the juncture of the cylindrical portions 20 of the flue therewith due to the internal pressure of the steam is practically non-existent and, consequently, any deformations of the annular portions 32 of the heads will be relatively small as compared with conventional practice wherein very small diameter flues are normally used. At the same time, the annular chamber 31 between the flue and the shell is of sufficient volume as to allow even distribution of heat from the steam and the shell, assuring substantially uniform heat transmission to the shell. It is important to maintain the annular chamber 31 of sufficient radial width as to avoid stratification of the flowing steam tending to create definite flow paths between the flue openings 29 and 30 which action would result in "dead" spots within the chamber 31 and uneven heat distribution of the shell.

The limits of flue diameter with respect to the shell diameter are approximately 60%-75%. A particular relationship between the shell wall thickness and the flue wall thickness also exists and, in this respect, the flue wall thickness should be from 1.25 to 2.0 times the shell thickness. Also, the wall thickness of those portions of the flue end sections which define the heads should be from 1.5 to 2.5 times the shell thickness, the same conditions prevailing when the heads are partly or wholly formed separately and removably attached to the flue.

Whereas the marginal edge 46 of one head 13 is rigidly secured as by fasteners 47 to its corresponding shell flange 11, the other head 14 is not rigidly attached at its marginal edge 48 to the shell. Instead, an annular or ring-like seal or bearing 49 is interposed between the circumferential edge of the head portion 48 and the inner edge of the shell flange 12. Preferably this bearing is of T-shaped cross section with the stem thereof received in a circumferential groove in the head 14. The bearing is preferably, though not necessarily, composed of two or more segments and it is also preferred that the bearing have an interference fit with the shell when the parts are initially assembled.

Since it would be impossible to obtain a proper seal by the use of the bearing alone, a deformable sealing ring 50 is provided. The sealing ring is of annular configuration and is generally semicircular in cross section, as shown, although this particular cross section need not be strictly adhered to since the cross section may be of any non-planar form suitable to accomplish the desired results. Two concentric anchor rings 51 and 52 are utilized in conjunction with the sealing ring 50, the inner ring 51 being secured as by fasteners 53 to the marginal edge of head 14 and the outer ring 52 being secured, as by fasteners 54 passing through flange 14, directly to the shell 10. The inner and outer edges of the sealing ring are welded throughout their lengths to the inner and outer anchor rings 51 and 52, respectively, so as to bridge and provide a seal across the parting faces between the head, bearing and shell.

To allow for relative sliding movement between head 14 and shell 10, the sealing ring 50 must be relatively thin-walled and deformable so as to avoid any material transfer of stress to the shell through the sealing ring. The relative sliding permitted between the head and shell compensates largely for any discrepancy in the expansion

and/or deformation between the shell and heads and the transfer of stress which might otherwise occur is manifested instead by such relative sliding.

Under working conditions, both the shell and the portion of the flue between the heads will tend to elongate due to the elevated steam temperature as compared with static, room temperature conditions. Also, the shell as well as the heads will tend to expand radially. It is of course impossible to constrain the expansion of the various parts so that no extra strain is induced in the members due to the normal discrepancies in expansion. However, the construction above described tends to minimize the stress transfer between shell and heads to such an extent that a shell thickness of only 1½ inches, heretofore unattainable, is permitted with the consequent increase in heat transfer rate between the inner and outer surfaces of the shell. This beneficial result is directly attributable to the provision of the massive flue in combination with the slip joint, the massive flue minimizing the distortion of the annular head portions 32 due to internal steam pressure and the slip joint reducing stress transfer between the parts to a practical minimum.

Although the above described slip joint construction utilized in conjunction with a "Yankee" drier does effect beneficial results even when utilized with a relatively small flue, the best results are attained by using a massive flue therewith such as was described above. It is to be understood that when the slip joint between one head and the shell is used with such massive flue, the relative sliding movement between head and shell is minimized. Also, a better face-to-face contact between the bearing and the shell is assured and consequently less friction is encountered therebetween.

It will be understood that the type of "Yankee" drier 35 which is under consideration will usually have a diameter in the order of 12 feet or more and a face width or length of about the same dimension. Understandably, when such a large drier is being used, the internal steam pressure, will produce considerable deformation 40 in the drier, particularly the shell thereof. In addition to the deformation produced by the internal steam pressure, there of course will be additional deformation caused by temperature differentials throughout the body of the drier and particular temperature differentials occurring between the inner and outer surfaces of the various component parts. These two deformation producing entities combine to create substantially all of the deformation which will be normally encountered during operation.

50 If conventional design is carried forward in a "Yankee" drier of the diameter and face or length width of the magnitude contemplated herein, the thickness of the shell must be at least two inches, if not more. In contrast to this, "Yankee" driers constructed in accordance with this invention, as hereinabove described, can be constructed with shell thicknesses of as little as 1½ inches which, of course, when compared with the two inch minimum of the prior art, denotes a 25% decrease in shell thickness and a corresponding increase of heat transfer through the shell.

The principles of this invention may be summarized by stating that the construction of the drier is such that the forces acting upon the heads and tending to deform the same will deform them in such a direction and manner that the portions of the heads which engage the shell or are secured thereto will tend to deform in the same direction as the shell when influenced by the deformation forces acting thereon. In other words, the construction of the drier is such as to permit the shell to deform in a normal manner and in the direction which would normally tend to occur with a minimum of interference from the heads and consequently with a minimum of aggravated stresses occurring particularly at the juncture of the fixed head and the shell.

I claim:

1. A Yankee drier or the like comprising a thin cylindrical shell, a head disposed at each end of said shell forming closures for the opposite ends thereof, one of said heads being rigidly connected in its marginal edge portion to said shell, an annular bearing interposed between the outer head and said shell to permit relative sliding between such other head and the shell, means for admitting steam under pressure into the drier, and means rigidly interconnecting central portions of said heads, said means being connected to the heads at a diameter approximately 60% to 75% of the diameter of said shell, and sealing means secured across the parting faces between the other head, the bearing and the shell.

2. The structure defined in and by claim 1 wherein said sealing means includes concentric inner and outer rings detachably secured respectively to said other head and the corresponding end of the shell, and an annular sealing ring of non-planar cross section having its inner and outer edges respectively sealed and secured throughout their lengths to said inner and outer annular rings respectively.

3. A Yankee drier or the like comprising a thin cylindrical shell, a head disposed at each end of said shell forming closures for the opposite ends thereof, one of said heads being rigidly connected at its marginal edge portion to said shell, an annular bearing interposed between the other head and said shell to permit relative sliding between such other head and the shell, means for admitting steam under pressure into the drier, means rigidly interconnecting central portions of said heads, said means being connected to the heads at a diameter approximately 60% to 75% of the diameter of said shell, sealing means secured across the parting faces between the other head, the bearing and the shell, said sealing means including concentric inner and outer rings detachably secured respectively to said other head and the corresponding end of the shell, and an annular ring of non-planar cross section having its inner and outer edges respectively sealed and secured throughout their lengths to said inner and outer annular rings respectively, said bearing being of T-shaped cross section with the stem thereof received in a circumferential groove in said other head, and said sealing ring being of semi-circular cross section.

4. A Yankee drier or the like comprising a thin cylindrical shell, a head disposed at each end of said shell forming closures for the opposite ends thereof, one of said heads being rigidly connected in its marginal edge portion to said shell, an annular bearing interposed between the other head and said shell to permit relative sliding between said such other head and the shell, sealing means secured across the parting faces between the other head, the bearing and the shell, means for admitting steam under pressure into the drier, and means rigidly interconnecting central portions of said heads, the last mentioned means being connected to the heads at a diameter approximately 60% to 75% of the diameter of said shell, the thickness of said shell being in the order of 1½ inches and the diameter of said shell being in the order of 12 feet.

5. A Yankee drier or the like providing for maximum heat transfer and for minimizing shell stresses therein, comprising an outer substantially cylindrical shell, head means closing the opposite ends of said shell, a hollow flue concentrically disposed within said shell and rigidly interconnecting said head means, the shell being rigidly secured at one end thereof to one of the head means, an annular bearing interposed between the other head means and the shell permitting relative longitudinal motion therebetween, sealing means secured across the parting faces between the other head, the bearing and the shell, means connected with the head means for rotatably mounting the drier, means for introducing

steam under pressure into the annular chamber defined between the flue and the shell, means for removing steam from said annular chamber, the diameter of said flue being from 60% to 75% of the diameter of said shell.

6. The structure defined in and by claim 5 wherein the thickness of said shell is in the order of 1½ inches and the diameter of the shell is approximately 12 feet.

7. The structure defined in and by claim 6 wherein the thickness of said flue is from 1.25 to 2.0 times the thickness of said shell, and the thickness of the head means at least in the area thereof radially outwardly from the juncture of the flue therewith is from 1.5 to 2.5 times the thickness of the shell.

15 8. A Yankee drier or the like comprising a cylindrical outer shell, a hollow flue disposed concentrically within said shell, a pair of heads closing the opposite ends of said shell, means rigidly securing one of the heads to the shell, bearing means interposed between the other head and an inner wall portion of said shell permitting relative sliding therebetween, inner and outer anchor rings detachably secured to said other head and the corresponding end of said shell respectively, and an annular sealing ring of semi-circular cross section having its inner and outer edges sealed and secured to the inner and outer anchor rings respectively.

20 9. A Yankee drier or the like comprising a cylindrical outer shell, a pair of heads closing the opposite ends of said shell, means rigidly interconnecting said heads, means rigidly securing one of the heads to the shell, the other head being slidably engaged with the shell, bearing means interposed between the other head and the inner wall portion of the shell to permit the relative sliding therebetween, said bearing being of T-shape cross section with the stem thereof received in a circumferential groove in said other head.

25 10. The structure as defined in and by claim 9 wherein sealing means is secured across the parting faces in the other head, the bearing and the shell, said sealing means including concentric inner and outer rings detachably secured respectively to the other head at the other end of the shell and an annular sealing ring of semi-circular cross section having its inner and outer edges respectively sealed and secured throughout their lengths to the inner and outer rings.

30 11. A Yankee drier or the like comprising a cylindrical outer shell, a hollow flue disposed concentrically within the shell, means for introducing steam under pressure into the space defined between the flue and the shell, and a pair of heads closing the opposite ends of the shell and rigid with said flue, one of said heads being rigidly secured to the shell, bearing means interposed between said shell and the other head such that said other head is slidably engaged with the shell, and sealing means secured across the parting faces between said other head and the shell, the flue diameter being from 60 percent to 75 percent of the diameter of said shell and the shell thickness being in the order of 1½ inches.

35 12. A Yankee drier or the like comprising a generally cylindrical outer shell, a head closing each end of the shell, bearing means on the heads for rotatably supporting the drier, and a hollow flue rigidly interconnecting the heads, one of said heads being rigidly attached to the shell, bearing means interposed between said shell and the other head such that said other head is slidably engaged with the shell, sealing means secured across the parting faces between said other head and the shell, means for circulating heating fluid from the interior of said flue to the interior of said shell, the flue diameter being of from 60 to 75 percent of the diameter of said shell to leave only a relatively small annular portion of each head which is disposed between the flue and the shell such that the outer marginal edges of the annular portions are deformable by the pressure and tempera-

ture differential existing under operating conditions only in directions outwardly from the drier to correspond with the direction of operating deformation of the shell portions with which they are engaged to thereby minimize stress transfer between the heads and the shell.
